UNITED STATES PATENT OFFICE.

ALEXANDER ROSS IRVINE, OF BROOKLYN, NEW YORK.

ENVELOPE OPENER.

Application filed May 26, 1926. Serial No. 111,870.

This invention relates to envelope openers and is more particularly adapted for use in connection with a finger ring, constituting a part of the ring, so that it may be worn on the finger and may be used while on the finger to perform its functions.

A further object is to provide an envelope opener which operates to sever the envelope flap at the point or line of juncture between the flap and the front of the envelope thus cleanly cutting the envelope without possibility of damage to the contents of the envelope.

A further object is to provide an envelope opener of this character which may not only be used in connection with a ring but on any other suitable support, which is ornamental and attractive in appearance, which is simple and inexpensive in construction, and which will most efficiently perform the functions for which it is intended.

With these and other objects in view, the invention consists in certain novel features of construction and combinations and arrangements of parts, which will be more fully hereinafter described and pointed out in the claim.

In the accompanying drawings—

Figure 1 is a perspective view, showing my improved device in the operation of opening an envelope;

Figure 2 is a top plan view of the device partly broken away;

Figure 3 is a view in side elevation of the device;

Figure 4 is a view in front elevation of the device, showing a fragment of the envelope in section during the process of cutting;

Figure 5 is a fragmentary plan inverted sectional view, showing the initial position of the device and the envelope prior to the cutting operation;

Figure 6 is a view similar to Figure 5 illustrating the cutting operation;

Figure 7 is a plan view, with the top plate removed, showing a modification;

Figure 8 is a view in section on the line 8—8 of Figure 7, with the top plate in position.

As my invention is particularly adapted for use in connection with a finger ring, I shall hereinafter so describe the same, with the understanding that I do not limit myself to this particular use.

1 represents a ring, which may be of any

material, ornamented in any suitable manner, and adapted to fit any finger or thumb of the hand.

On this ring a base plate 2 is rigidly fixed. 60 A top or outer plate 3 is located above the baseplate 2 and spaced therefrom, and between these plates 2 and 3 a blade holder 4 and a blade 5 are located.

I do not limit myself to the particular 65 manner of spacing the blade holder and blade from the respective plates, as this may be done in many ways. I may employ, for example, suitable cement or solder, which may when set constitute spacers 6, or I may employ properly shaped and formed blocks for the purpose. These spacers or material only extend part way of the width of the upper and lower plates 3 and 2 so that the envelope opener at its operative edge is in 70 effect bifurcated or formed with a longitudinal groove or recess in which a portion of the blade holder 4 and the blade 5 are located.

This blade holder 4 may be made and secured in various ways. A simple form is illustrated in Figure 3, in which the blade holder 4 constitutes a plate having a tapering recess 7 therein, with the blade 5 secured to the forward portion of the blade holder, 80 and having its cutting edge 9 projecting inwardly beyond the edge of the blade holder so as to be in position for cutting operation, as will more fully hereinafter appear.

The free end of the blade 5 may be shaped 90 in any desired manner for convenience in finding its position for cutting, and I have illustrated the same as slightly bent at its free end, as shown at 10.

I would call particular attention to the 95 fact that the blade holder 4 is preferably spaced farther from the plate 3 than it is from the plate 2 so as to accommodate between the blade and the plate 3 the thicker portion of the envelope or contents of the 100 envelope to prevent severing of the same.

In the modification illustrated in Figures 7 and 8 I show a modified form of blade holder 11 and blade 12, which are pivotally connected at one corner, as shown at 13, so 105 as to allow the blade and blade holder to be swung outwardly to the dotted line position for sharpening or removal. A threaded pin 14 may be employed as a pivot, which is removable to allow the complete removal of 110 the blade holder and blade.

To insure the blade remaining in opera-

tive position, the latter may be punched or otherwise depressed, as shown at 15, to seat in a correspondingly shaped recess, as clearly indicated in Figure 8.

- 5 It will be noted that with all forms of my invention a rigid block or support is provided which is grooved in one edge and has located in its grooved portion a cutter or blade which preferably tapers toward its free end.

10 In operation, the envelope is placed in the position indicated in Figure 5, with the body of the envelope between the blade and the outer plate 3. When the ring or the envelope is moved in the proper direction the end of the blade will contact with the fold line of the envelope flap, and then the envelope can be given a quarter turn to 15 position the same and sever the fold line of the envelope when the latter is drawn longitudinally, as indicated in Figure 6.

15 I thus provide a very simple, efficient and ornamental device, which can be sold to the trade at a reasonable price, and which can 20 be used for opening envelopes without any possibility or danger of injuring the contents.

Figure 1 illustrates in perspective the operation of opening an envelope, the latter indicated by the reference numeral 14. The 30 ring 1 is shown on the finger of one hand 15 while the thumb 16 and finger of the other hand are used to grip the envelope and manipulate the same.

35 Various slight changes and alterations might be made in the general form of the parts described without departing from the invention and hence I do not limit myself to the precise details set forth but consider myself at liberty to make such slight changes 40 and alterations as fairly fall within the spirit and scope of the appended claim.

I claim:

An envelope opener, comprising a block 45 having a groove in one face and a blade having an inner cutting edge located within the groove of the block, said blade secured to the block at one end and tapering toward its free end, said blade having its free end so shaped as to be laterally offset with relation 50 to the walls of the groove whereby the end of the blade may find its position in a fold for cutting.

ALEXANDER ROSS IRVINE
